HIGH INTENSITY LAMP

Dan M. Andre, 8843 Kostner Terrace,
Skokie, Ill. 60076

Filed Apr. 29, 1970, Ser. No. 22,713

Term of patent 3½ years

Int. Cl. D26—02

U.S. Cl. D48—20

FIG. 1 is a perspective view of a high intensity lamp illustrating my new design;

FIG. 2 is a side elevational view thereof on an enlarged scale;

FIG. 3 is a front elevational view thereof on an enlarged scale;

FIG. 4 is a top plan view thereof on an enlarged scale.

I claim:

The ornamental design for a high intensity lamp, substantially as shown.
